UNITED STATES PATENT OFFICE.

JOHN E. GANTENBEIN, OF KELSO, WASHINGTON.

LIMB ATTACHMENT.

Application filed November 30, 1921. Serial No. 518,963.

To all whom it may concern:

Be it known that I, JOHN E. GANTENBEIN, a citizen of the United States, and resident of Kelso, in the county of Cowlitz and State 5 of Washington, have invented certain new and useful Improvements in Limb Attachments, of which the following is a specification.

This invention relates to limb attachments especially adapted for use in connection with high shoes.

An important object is to provide an attachment for the forelimb which overlaps the shoe tops and thereby prevents foreign 15 matter such as dirt and snow from entering the shoe tops.

In addition to forming a means for excluding foreign matter the improved limb attachment is a means for bracing the fore 20 limbs and for keeping the same warm in cold weather.

Further the invention forming the subject matter of this application aims to provide an attachment of the character specified 25 which is simple to apply, neat in appearance and cheap to manufacture.

Other objects and advantages of the invention will be apparent during the course 30 of the following description.

In the accompanying drawing forming a part of this application and in which like numerals are employed to designate like parts throughout the same,

Figure 1 is a perspective illustrating the 35 manner in which the improved attachment is applied.

Figure 2 is a perspective of the attachment applied.

Figure 3 is a plan view of the attachment.

In the drawing wherein for the purpose of illustration is shown a preferred embodiment of the invention, the numeral 5 designates a forelimb or leg, the foot of which 45 is extended into a shoe 6 provided with the usual top 7.

The invention forming the subject matter of this application is especially adapted for use in connection with high shoes although 50 if desired the inventive idea may be carried out in connection with low shoes. The attachment consists of a body 8 formed of elastic material adapted to encircle the forelimb and the adjacent portions of the shoe 55 tops 7 in the manner illustrated in Figure 2.

The vertical edge portions of the elastic body 8 is provided with leather strips 10 having eyelets 11 of any suitable type and through which a lace 14 is extended. The lace may begin at the upper edge of the 60 body and may extend to the lower portion of the attachment, or it may begin at the lower portion of the attachment and extend to the top of the same.

One of the leather strips is provided with 65 a flap 16 which overlaps the other leather strip 10 and prevents the lace from cutting into the flesh and also acts as a means for preventing the entrance of foreign matter between the edges of the leather strips. 70

In the manufacture of the improved attachment the elastic body may be provided at its lower end and between its edges with a leather wear strip 18 which contacts with the rear side of the shoe top 7. 75

In practice the elastic body 8 is of a size to firmly grip the forelimb and is capable of yielding when the limb is moved, whereby the ligaments in the fore portion of the limb are not tightly gripped by the body. 80

As the body 8 extends a substantial distance over the shoe top 7 foreign matter such as snow and dirt is prevented from entering the shoe tops. The attachment may be readily and conveniently applied and 85 does not detract from one's appearance.

Having thus described the invention what I claim as new and desire to secure by Letters Patent is:—

An attachment for the limbs comprising 90 an elastic body adapted to embrace the fore limb and to overlap the upper portion of a shoe top whereby to exclude foreign matter, leather strips secured along the vertical edge portions of said elastic body and having eyelets, a lace engaged with said eyelets to secure the elastic body about the fore limb, whereby the elastic body embraces the limb and keeps the same warm, and a flap carried by the vertical edge portion of one of said 95 leather strips and adapted to overlap the other strip, and a narrow transversely extending leather strip secured to the lower edge portion of the elastic body between the vertical edges of the same and constituting a 100 wear member between the shoe and the elastic body, said first named leather strips forming a means to hold the elastic body against transverse stretching. 105

JOHN E. GANTENBEIN.
